GRINDING MACHINE

Erwin G. Roehm, Norwood, Ohio, assignor to
 Cincinnati Grinders Incorporated, Cincinnati,
 Ohio, a corporation of Ohio

Application November 5, 1934, Serial No. 751,864

24 Claims. (CL 51—103)

This invention relates to improvements in machine tool structures, and particularly to an attachment or sizing device for use with grinding machines.

5 One of the principal objects of the invention is the provision of a sizing device adapted to operate when the work is either above the desired size or below said size to effect a correction of the position of the parts so that subsequent work pieces are reduced to the desired size.

Another object of the invention is the provision of a very sensitive device utilizing hydraulic pressures for the control and amplifying means whereby minute variations from the normal or 15 desired sizes releases the amplifying pressures for effecting the operation of the control mechanism.

A further object of the invention is the provision of a sizing device which is particularly adapted for use with centerless grinders for producing successive work pieces to the same desired size and in which the sizing device controls the size of the grinding throat for enlarging said throat if the work pieces produced are under the 25 desired size and for contracting said throat if the work pieces are over the desired size.

A further object of the invention is the provision of a sizing device as above specified in which the increments of feed as effected thereby may be varied for thereby varying the tolerance within 30 which the work pieces may be produced.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the 40 invention.

In the drawings:

Figure 1 is a rear elevational view of a centerless grinder embodying the improvements of this 45 invention.

Figure 2 is a top plan view of the machine shown in Figure 1.

Figure 3 is a fragmentary longitudinal, sectional view through the machine taken on line 50 3—3 on Figure 2.

Figure 4 is a sectional view through the housing enclosing the operating mechanism as seen from line 4—4 on Figure 1.

55 Figure 5 is a sectional view through the feeler

mechanism which is engaged by the finished work piece as seen from line 5—5 on Figure 3.

Figure 6 is a sectional view through the delay valve which insures the work being properly positioned relative to the gaging mechanism before 5 the operation thereof.

Figure 7 is a sectional view through the cut-off valve which insures the machine being properly set up before placed in use.

Figure 8 is a sectional view through the feeding 10 mechanism which is coupled with the sizing device and operated thereby; the figure being as seen substantially from line 8—8 on Figure 3.

Figure 9 is a sectional view showing the parts operated by the sizing device in elevation as seen 15 from line 9—9 on Figure 8.

Figure 10 is a sectional view taken substantially at right angles to Figure 9 as seen from line 10—10 on Figure 8.

Figure 11 is a sectional view through the dia- 20 phragm valve mechanism as seen from line 11—11 on Figure 4.

Figure 12 is a view as seen substantially from line 12—12 on Figure 1 and illustrates in elevation the throat of a centerless grinder with the 25 improved sizing device in position relative thereto.

Figure 13 is a diagrammatic view of the hydraulic circuit involved in this invention.

Figure 14 is a sectional view taken at right angles to Figure 9 as seen from line 14—14 on 30 Figure 9.

Figure 15 is a sectional view through a pressure operated switch and forming a detail of the invention.

Throughout the several views of the drawings 35 similar reference characters are employed to denote the same or similar parts.

As was noted above, this invention pertains primarily to a sizing device for controlling the size of work pieces as they are produced by a machine 40 tool. In view of the fact that grinding machines are adapted to produce series of work pieces, all within very close fractional limits of one another and a predetermined size, the invention is 45 illustrated in connection therewith. Centerless grinders are frequently set up and run day after day on the same work piece, such as wrist pins as utilized in internal combustion engines, the machines being shut down at night and started up again in the morning without changing the type 50 or size of the work pieces being operated upon. As is usual practice, the cooling fluid is copiously supplied to the grinding wheel during the grinding operation to keep said wheel and the work being operated upon in a cool state.

prises a supporting member 62 having oppositely inclined faces 63 and 64 near its upper end. Disposed on said inclined faces respectively are supporting blades 65 and 66 adjustable respectively relative to plates 67 and 68 secured to the faces 63 and 64. The means for adjusting the supporting blades relative to their plates is shown in Figure 3 in connection with the blade 66 and since the structure thereof is clear from the drawings no further description is deemed necessary.

The supporting member 62 is adapted to be vertically adjusted relative to the bracket 61 for which purpose the said bracket has projecting therefrom a shelf 69 on which is disposed a jack screw 70 engaging on its upper end with the member 62 and whereby it is positioned to accurately align the supporting blades 65 and 66 with the work rest blade 27 so as to receive the work from the said blade.

Disposed above the supporting blades 65 and 66 is the sizing device which includes a housing 71 disposed in a guideway 12 in the bracket 61. In order to adjust the housing 71 relative to the bracket 61 and toward and from the supporting blades 65 and 66 the bracket 61 has projecting therefrom a nut 73 through which is threaded an adjusting screw 74 having at its lower end a swivel connection with the housing 71 and at its upper end a knob 75 whereby the screw 74 is rotated. Between the work rest blade 27 and the work supporting blades 65 and 66 is a cleaning mechanism for removing from the surface of the work moisture and foreign matter such as grit from the wheel before the work is presented to the gaging mechanism. This mechanism comprises a ring or circular member 76 secured to the bracket 61. Fastened to the outer face of the ring 76 is a wiper 77 adapted as the work passes through the ring to clean the surface thereof, whereby no extraneous matter influences the gaging of the work.

The structure of the sizing device is shown in Figure 5 and comprises a plunger 78 having the feeler point 79 projecting beyond the housing 71. The plunger 78 is held in position for vertical movement by a pair of flexible diaphragms 80 and 81 respectively held in operative position by cap plates 82 and 83 and it is through the latter which the contact member 79 projects. The other or upper end of the plunger 78 is provided with a knife edge 84 disposed in a notch 85 in a lever 86. One end of the lever 86 is secured to the diaphragm 81 held in position by a plug 88 screwed into a flange 89 integral with the upper cap 82. The outer end of the lever 86 contacts with the lower end 90 of a valve member 91, and in addition, supports an electrical contact 92 to which one wire 93 of an electrical circuit is secured. The contact 92 is adapted to engage a spring arm electrical contact 94 secured to a binding post 95 disposed within the housing 71 and to this binding post the second wire 96 of the electrical circuit is secured.

The movement of the plunger 78 by the work 60 first breaks the electrical circuit by separating contacts 92 and 94 and then positions the valve member 91 in accordance with the size of the work being gaged. The separation of the electrical contacts sets in operation the gaging mechanism, as will now be described with particular reference to the hydraulic diagram, Figure 13. During the description of the hydraulic circuit the various valve mechanisms and their operating means will be described in detail with

reference to the several structural views in which they are shown.

The wires 93 and 96 are connected to a solenoid 97 which sets the compensating mechanism in operation when the work piece is disposed in position to be operated upon. For this purpose the solenoid is connected with a valve mechanism indicated in general in Figure 13 by the reference character 98. This valve mechanism 98 is normally held by the solenoid in an inoperative position as shown in Figures 6 and 13. Upon de-energization of the solenoid, when the contacts 92 and 94 are separated, the valve mechanism is yieldably shifted to its operative position.

The specific mechanism is shown in Figures 4 15 and 6 as follows:

The core 99 of the solenoid 97 has pivotally connected therewith one end of a link 100 which has its other end pivotally connected to an arm 101 pivoted intermediate its ends at 102 to the valve housing 103 of the valve mechanism 98. The second or reduced end 104 of the arm 101 is received in a transverse groove or notch 105 formed in the stem of valve member 106. The solenoid 97, in normally retaining the valve mechanism 98 inoperative, holds under tension a spring 107 having one end connected to the arm 101 and the other end connected to the outside of the valve housing 103. The valve mechanism 98 and the solenoid 97 are supported and enclosed by a suitable bracket 108 secured to the rear of the bed 15.

As seen in Figure 6, the valve member 106 is disposed for sliding movement in a valve bushing 108 pressed into the casing 103. The bushing 108 is provided therethrough with two sets of radial ports 109 and 110, each set being encircled by a similar circumferential groove 111 formed in the exterior of the bushing 108. The valve member 106 is provided with a reduced portion 40 or cannelure 112 adapted when in the position shown in Figure 6 to interrupt communication between the ports 109 and 110 and when in its second or lower position to establish communication therebetween.

The bushing 108 at the lower end of the bore for the valve member 106 carries a one-way check valve 112 which forms a chamber at the bottom of the valve member 106. The said chamber 113 is connected by a port 114 with a discharge port 115. Between the ports 114 and 115 the bushing 108 carries an adjustable choke or throttle valve 116 past which the medium in the chamber 113 must be forced into the discharge port 115.

By reference to Figure 13 it will be noted that the ports 109 have connected therewith one end of a pipe or conduit 117 which terminates at its other end in the sizing valve mechanism indicated in general in Figure 13 by the reference numeral 118. The ports 110 have connected therewith one end of a pipe or conduit 119 which terminates in the pressure pipe or conduit 120 terminating at its other end in a circulating pump 121. The pipe or conduit 120 has a by-pass pipe or conduit 122 containing a relief valve 123 which determines the pressure in the pipe 120 and therefore the operating pressure in the system. Extending from the other side of the pump 121 is the suction pipe 124 terminating in 70 the sump or tank 125 which may be located interiorly of the machine bed, or a separate tank may be utilized and disposed exteriorly thereof.

Upon de-energization of the solenoid 97 the spring 107 actuates the arms 101, as seen in Fig-

ure 4, for urging the valve member 106 downward. This causes the hydraulic medium in the chamber 113 to be forced outwardly through the ports 114 and 115 to the pipe or conduit 126, see 5 Figure 13, which is connected with the discharge port 115 and the sump or tank 125. The valve member 106 is held in its upper or shut-off position by hydraulic pressure which enters the chamber 113 through the one-way check valve 112. For this purpose the check valve 112 is connected with one end of a pipe or conduit 127 which has its other end connected with the pressure pipe or conduit 120.

The downward movement of the valve member 106, as effected by the spring 107, is retarded by the adjustable throttle or choke valve 116, thereby effecting a time interval or delay between the opening of the contacts 92 and 94 and the actual gaging operation and the operation of the mechanism controlled thereby. It will be appreciated, however, that as soon as the valve member 106 is depressed to its operative position the pressure in the pipes or conduits 120 and 119 is connected with the pipe or conduit 117 and therefore the 10 valve mechanism 118. This valve mechanism 118 is shown structurally in Figure 5 and includes the valve member 91 from which the conical point 90 projects. This valve member 91 is disposed in a valve bushing 128 pressed into the 15 housing 71. The valve bushing 128 is provided with a plurality of sets of radial ports 129, 130, 131 and 132, each set being encircled by a similar circumferential groove 133 formed in the exterior of the bushing 128. Within the bushing 128 the 20 valve member 91 is provided with a plurality of piston portions for forming reduced portions or cannelures 134 and 135 adapted respectively to connect the ports 131 and 130, and 131 and 132, depending upon the position of the valve member 25 91. The bushing 128 is provided, interiorly thereof with a groove 136 which connects the central ports 131 and the groove 136 is of such a width as to be substantially sealed by the piston portion 137 on the valve member 91 when 30 the said valve member is in its central position such as would be the position when the work piece being gaged is of the proper or desired size as shown, for example, in Figure 5.

As was noted above, the lower end or conical point 90 of the valve member 91 rides on the outer end of the arm 86 and in order to maintain this condition the valve member 91 has contacting with its upper end one end of a spring 138, the other end of which contacts with 35 a plug 140 threaded into the end of the bushing 128. The valve bushing 128, and therefore the valve member 91, are adapted to be axially adjusted relative to the housing 71. For this purpose the housing has threaded into it a nut member 141, which is in turn threaded to the bushing 128. As is usual practice, the two threaded 40 connections are of different leads whereby a differential threaded connection is had between the parts so that the adjustment of the bushing 128 may be extremely fine and accurate. As seen 45 in Figure 13, the pipe or conduit 117 from the valve mechanism 98 is connected with the central set of ports 131 of the bushing 128, while the ports 130 and 132 have respectively connected therewith one end of pipes or conduits 142 and 143 which terminate at their other ends in a diaphragm valve mechanism indicated in general in Figure 13 by the reference numeral 144. The remaining ports 129 and 316 have connected 50 therewith one end of a pipe or conduit 145 which

terminates in the sump or tank 125 and serves as a drain for returning to the sump any fluid that may leak past the valve member 91.

The diaphragm valve mechanism 144 is shown structurally in Figure 11. This mechanism comprises three housings 146, 147 and 148 secured to one another and having between the upper housing 146 and intermediate housing 147 a flexible diaphragm 149 and a similar diaphragm 150 between the other side of the intermediate housing 147 and lower housing 148. The diaphragms 149 and 150 form between them a chamber 151, while the diaphragm 149 forms within the housing 146 a second chamber 152 and the diaphragm 150 forms within the housing 148 a third chamber 153. Carried by the housing 146 is a sleeve 154 through which is formed a port 155 having formed at its inner end a valve seat adapted to be engaged by a valve 156 carried by the diaphragm 149. The housing 148 carries a similar 10 sleeve 157 having formed therethrough a port 158 with a valve seat at its inner end likewise contacted by a valve 159 carried by the diaphragm 150.

The chamber 152 within the housing 146 has 15 communicating therewith a pair of ports 160 and 161 formed in the housing 146 at substantially diametrical points thereof. The housing 147 likewise has formed therethrough a pair of ports 162 and 163 which communicate with the chamber 151 formed within said housing between the diaphragms 149 and 150. The housing 148 also is provided with a pair of diametrical ports 164 and 165 which communicate with the chamber 153 within the housing 148.

By reference to Figure 13 it will be noted that the pipe or conduit 142 is connected with the port 164 of the housing 148, while the port 160 of the housing 146 has connected therewith the end of the pipe or conduit 143. The sleeve port 155 has connected therewith the terminus of the pressure pipe or conduit 120, while the other sleeve port 158 has connected therewith one end or terminus of a pipe or conduit 166 which extends from the pressure pipe or conduit 120. The port 162 of the housing 147 is likewise connected with one end of a pipe or conduit 167 which extends from the pressure pipe or conduit 120. The pipe or conduit 167, however, has therein a choke or needle valve 168 which effects a pressure drop between the pipe or conduit 120 and the chamber 151. From the foregoing it will be noted that the diaphragm valves 156 and 159 have respectively acting thereon the full pressure, tending to unseat said valves. Opposed to this, however, is the pressure within the chamber 151 as effected by the hydraulic resistance valve 168 which, while lower than that acting on the valve, acts on a greater area for thereby preventing the unseating of said valves 156 and 159.

The port 161 of the housing 146 has connected therewith one end of a pipe or conduit 169 which terminates on its other end in a hydraulic plunger mechanism indicated in general in Figure 13 by the reference numeral 170. The pipe or conduit 169 is further connected by way of a branch conduit 171 with a valve mechanism indicated in general in Figure 13 by the reference numeral 172. The corresponding port 165 of the housing 148 has connected therewith one end of a pipe or conduit 173 which terminates on its other end in a hydraulic plunger mechanism indicated in general in Figure 13 by the reference character 174 and it should be noted that the plunger 75

mechanism 174 is similar in all respects with the plunger mechanism 170, which will be described in detail later. The pipe or conduit 173 is connected with the valve mechanism 172 by a branch pipe or conduit 175. The ports 163 of the intermediate housing 147 have connected therewith the upper end of the discharge pipe or conduit 126 which contains a hydraulic resistance or choke coil 176 which maintains a back pressure in the chamber 151 to hold the diaphragm valves to their seats as explained above.

The plunger mechanisms 170 and 174 and the parts operated thereby are shown structurally in Figures 8, 9, 10, and 14 and comprise a housing 176 secured to a flange 177 on the end of the swivel bracket 53 and disposed between said bracket and the hand wheel 56. The housing 176 has secured therein a pair of sleeves or cylinders 178 and 179 respectively encircling pistons 180 and 181 of plungers 182 and 183. The plungers 182 and 183 are respectively associated with the plunger mechanisms 170 and 174. The plunger 182 has secured to its lower end a second piston portion 184, while the plunger 183 has likewise secured to its lower end a second piston 185. The said pistons 184 and 185 are respectively disposed within sleeves or cylinders 186 and 187 carried by the lower end of the housing 176, while the cylinders 178 and 179 are carried by the upper end thereof.

The upper end of cylinder 178 is closed by a plug 188 through which is formed a port 189, while the cylinder 179 is likewise closed by a plug 190 through which is formed a port 191. The lower cylinders 186 and 187 are respectively provided with a set of radial ports 192 and 193, each set being encircled by a groove 194 and 195 respectively formed in the exterior of the cylinders 186 and 187.

By reference to Figure 13 it will be noted that the pipe or conduit 169 from the diaphragm valve mechanism 144 terminates in the port 189 for the cylinder 178, while the pipe or conduit 173 terminates in the port 191 of the cylinder 179. By reference to Figure 9 it will be noted that the housing 176 is provided with a port 196 communicating at opposite ends with the radial ports 193 in the cylinder 187 and radial ports 192 in the cylinder 186. Connected with the port 196 is a pipe or conduit 197 which extends from the main pressure pipe or conduit 120.

Each of the plungers 182 and 183 has pivotally secured thereto an L-shaped pawl 198 and 199 and adapted respectively to engage the teeth of a ratchet 200 and 201. As shown in Figure 10, the ratchets 200 and 201 are integral with one another, and as shown in Figure 9, have their teeth extending in opposite directions wherefore the pawls 198 and 199 engage with their respective ratchets at diametrical points. The ratchets 200 and 201 are secured to one end of a worm shaft 202 rotatably journaled in suitable bearings provided by the housing 176. The worm shaft 202 has keyed thereon a pair of worms 203 and 204, the latter being mounted for sliding movement, while the former is fast on the shaft. Surrounding the shaft and abutting on one end with the worm 204 is a spring 205 which abuts on the other end with one of the bearings carried by the housing 176. The tension in the spring 205 effectively removes backlash between the teeth of the worms 203 and 204 and a worm wheel 206 with which said worms mesh. The worm wheel 206 is loosely mounted on the shaft 52 journaled within the swivel bracket 53.

Keyed to the shaft 52 is a sleeve 207 which provides a spline connection and sliding bearing for a clutch member 208 which is provided on its inner end with a conical clutch face adapted to engage a contragenerically formed clutch face on the worm wheel 206. In order to disengage the clutch member 208 from the worm wheel the said clutch member is provided with a circumferential groove 209 receiving therein a roller eccentrically connected with a shaft 210 which projects beyond the housing 176 to receive a handle 211. Rotation of the shaft 210 by the handle 211 will, as will readily be understood, disengage the conical clutch faces whereby the shaft 52 may be actuated by the hand wheel 56. In order to hold the conical clutch faces in engagement with one another when the worm wheel 206 is to be connected with the shaft 52 there is provided a spring pressed plunger 212 contacting with the clutch member 208.

From the foregoing it will be noted that, depending upon which of the plungers 182 and 183 is actuated, will depend the direction of rotation of the shaft 202 and therefore the direction of rotation of the worm 206 and shaft 52. From this it follows that the oscillation of the grinding wheel carriage toward or from the axis of the work will be controlled by the size of the work being gaged. In order to determine the amount of rotation of the shaft 202 in either direction as effected by the movement of the plungers 182 or 183 the housing 176 has threaded therethrough a pair of adjusting screws 213 and 214 respectively engaging the tails 215 and 216 of the pawls 198 and 199. To actuate the said pawls 198 and 199 into engagement with their respective ratchets, there is provided spring pressed plungers 217 and 218 respectively acting on pawls 198 and 199.

Continuing now with the hydraulic circuit as shown in Figure 13, each of the pipes or conduits 169 and 173 respectively have therein a one way check valve 219 and 220 which permits a flow through said pipes or conduits to the plungers but not from the plungers. Extending from each of said pipes or conduits from a point between their one-way check valves and their connection with the plunger mechanisms are pipes or conduits 221 and 222 which terminate in the valve mechanism 172. This valve mechanism 172 is shown structurally in Figure 10, and as there shown, comprises a valve bushing 223 pressed into a suitable bore formed in a housing 176. The valve bushing 223 is provided with a plurality of sets of radial ports 224, 225, 226, 227, 228, 229, 230, 231, 232 and 233, each set of ports being encircled by a similar circumferential groove 234 formed in the exterior of the bushing. Disposed within the bore in the bushing 223 is a valve member 235 provided with a plurality of piston portions forming there between reduced portions or cannelures for connecting the ports in different combinations, depending upon the position thereof.

As seen in Figure 13, the ports 225 have connected therewith the pipe or conduit 171 from the pipe or conduit 169, while the ports 229 have connected therewith the pipe or conduit 175 from the pipe or conduit 173. The ports 221 and 231 have respectively connected therewith the pipes 221 and 222. The ports 224, 226, 230, and 233 have respectively connected therewith branch discharge conduits which empty into pipe or conduit 236, 70 emptying in turn into pipe or conduit 126. The remaining ports 228 and 232 have connected therewith branch pipes or conduits 237 and 238 which empty into pipe or conduit 239, terminating in the sump or tank 125.

The means for shifting the valve member 235 is shown in Figures 9 and 10 and for this purpose the said valve member has projecting therefrom a valve stem 240 having formed at its outer end a circumferential groove 241 receiving shifter pins 242 projecting from the forked end 243 of a lever 244. The lever 244 depends from a sleeve 245 rotatably mounted on a rod or shaft 246 carried by the walls of the housing 176 interiorly thereof. 5 Projecting rearwardly from the sleeve 245 is a pair of arms 247 and 248 adapted to be respectively engaged by an abutment or finger 249 projecting from the plungers 182 and 183 when either of said plungers reaches its lowermost position. Projecting upwardly from the sleeve 245 above each 10 arm 247 and 248 is a lug 250 adapted to be engaged by a spring actuated latch 251 for holding the valve member 235 in the position to which it was shifted by the plunger acting through its abutment and the arms on the sleeve 245.

The movement of the valve member 235 by the said plunger is against the resistance of a spring 252 which is disposed within the bore in the bushing 223 and surrounds the valve stem 240. As 15 soon as the plunger is returned to its normal or upper position the upper surface of the lugs 249 engage a projecting abutment 253 on the latches 251 for releasing the lugs 250 whereupon the spring 252 shifts the valve member 235 to the 20 position shown.

The operation of the mechanism so far described is as follows:

Assuming the contacts 92 and 94 are closed and a work piece has just passed beneath the sizing plunger 78 and has shifted same upwardly, thereby breaking the contacts 92 and 94, the de-energization of solenoid 97 permits the spring 101 to oscillate the arm 101 and thereby yieldably actuate the valve member 106 downwardly. This 35 movement of the valve member 106 is retarded since the said valve member must discharge the fluid within the chamber 113 out through the port 114, choke valve 116, and port 115 to the discharge conduit 126 and the sump or tank 25. 40 As was noted above, this delay in the movement 45 of the valve member 106 permits the work piece to be actuated further beneath the sizing member and further prevents the operation of the mechanism as would be effected should a small gap 50 develop between successive work pieces.

The valve member 106 continues to descend until the pipes or conduits 120, 119 and 117 are connected with one another, thereby delivering the pressure to the sizing valve mechanism 118. With 55 the valve member 91 in the position shown, no flow is had through the pipe or conduit 117 since its ports 131 are completely closed by the piston portion 137 on the valve member 91'. No further flow is therefore had through the hydraulic circuit.

It should be noted, however, that there is a small flow through the pipe or conduit 120, pipe or conduit 167, hydraulic resistance or choke valve 168, chamber 151 in the diaphragm valve mechanism 144, and pipe or conduit 126. This 65 flow is just sufficient to set up a pressure within the chamber 151 to hold the valves 156 and 159 to their seats to prevent any flow through the sleeve ports 155 and 158 and chambers 152 and 153.

Assuming now that a work piece above the normal size, as shown in Figure 5, were placed beneath the plunger 78, which would result in a movement of the lever 86 to a point above that shown in Figure 5, the lever 86 would shift the 70

valve member 91 upwardly for cracking or opening the ports 131 into the cannelure 135. This, then, would cause a flow of the pressure medium from the pump 121 through pipes or conduits 120, 119, and 117 to the valve mechanism 118 5 where it would be connected with the pipe or conduit 143 and therefore the chamber 152 in the diaphragm valve mechanism 144. This flow or pressure acts on the diaphragm 149 which is greater than that within the chamber 151, wherefore the valve 156 is removed from its seat. The unseating of the valve 156 connects the full pump pressure in the pipe or conduit 120 with the chamber 152 and therefore the outlet conduit 169 and the piston plunger mechanism 170. 10

The cracking of the ports 131 by the piston portion 137 sets up a resistance to the flow of the medium through the valve mechanism. This flow is maintained in the pipe or conduit 143 by the hydraulic resistance or adjustable choke valve 20 386. The reaction of these resistances on the flow establishes a pressure which is below the full pressure, as in the pipes or conduits 120, 119, and 117. This pressure, however, when in the chamber 152 is sufficient to operate the diaphragm 149 25 for unseating the valve 156 as above described. Since the hydraulic resistance or valve 286 is adjustable this pressure in the chamber 152 may be varied, thereby requiring a greater or lesser cracking or opening of the ports 131, which means 30 that the tolerance of the work may be varied before the compensating mechanism will be set in operation.

As will later be made clear, an undersize work piece likewise cracks the ports 131 for permitting 35 a flow into the pipe or conduit 142. This cracking of the ports again sets up a hydraulic resistance which, combined with the adjustable hydraulic resistance or choke valve 285 in the pipe or conduit 142 determines the pressure in the 40 chamber 153 for unseating the valve 150. Since the valve 285 is adjustable, the pressure in this chamber may be varied to require a greater or lesser opening of the ports 131 before the diaphragm 150 is operated. 45

It will be appreciated that the central port 131 is cracked to permit a flow into the valve mechanism 118 which will be sufficient to operate the compensating mechanism as when a work piece is between the actual size and the upper and lower tolerance limits. This will cause a flow through the pipe or conduit 117 and valve mechanism 118. To relieve this flow the valve bushing 128 is provided with ports 315 and 316, see Figure 13, with which is respectively connected one end 55 of pipes or conduits 317 and 318 terminating at their other ends in the drain pipe or conduit 145, which terminates in the tank 125. It should be noted that as soon as the valve member is moved to the position representative of either the high 60 or low limit of tolerance the said drain ports 315 and 316 are closed.

The full pump pressure acting on the upper piston 180 of the plunger 182 forces same downwardly, together with its pawl 198. The pawl 198, 65 as seen in Figure 9, engages its ratchet 200 for rotating same in a clockwise direction for correspondingly rotating the worm shaft 202. This rotation of the worm shaft 202 through the worm wheel 206 rotates the shaft 52 and the worms 50 70 and 51 thereon. The rotation of the worms 50 and 51 correspondingly rotate the worm wheel 49 and the jack screw 47 for lowering the plunger 44 and effecting a counterclockwise oscillation of the grinding wheel carriage, as seen in Figure 3. 75

As soon as the plunger 182 reaches its lowermost position the abutment 249 thereon engages the arm 248 of the sleeve and lever mechanism 245-244 for actuating same in a counterclockwise direction as seen in Figure 10, and thereby shifting the valve member 235 to its second operative position, that to the right of the position shown in Figure 13. With the valve in this position the pipe or conduit 169 is connected through the pipe or conduit 171 with the valve mechanism 172 and discharge conduits 236 and 226 with the sump or tank 125, thereby relieving the pressure above the plunger 182. The hydraulic medium under pressure in pipe or conduit 120 flows through the branch pressure pipe or conduit 197 to the port 196 and acts on the piston portion 184 at the bottom of the plunger 182 and effects the return or upward movement of said plunger. The medium ahead of the plunger is now discharged through the pipe or conduit 221 since it cannot pass the one-way check valve 219. This pipe or conduit 221 is connected through the valve mechanism 172 with discharge pipes or conduits 231 and 239 with the sump or tank 125. The flow through this pipe, however, is considerably retarded by the hydraulic resistance or choke valve 254, thereby retarding the upward movement of the said plunger 182. The reason for this hydraulic resistance 254 is to allow a time interval in which the work piece, which was gaged, is removed from beneath the plunger 18 and a new work piece, which has been further reduced due to the adjustment of the parts as just described, to be placed in position for gaging. As soon as the plunger 182 reaches its uppermost position the latch 251 is raised by the abutment 249, whereupon the spring 252 fires the valve member 235 to the position shown in Figure 13.

From the foregoing it will now be understood that there has been provided a hydraulically actuated gaging mechanism for further reducing a second work piece, should the first be above the desired or accurate size.

In the event the work piece is below the desired or proper size the operation of the mechanism is as follows:

The plunger 18 would under these circumstances not be elevated as high as shown in Figure 5, which would position the valve member 235 at a point below that shown, and open the central ports 131 to the ports 130. Under these circumstances the hydraulic medium in pipes or conduits 120, 119 and 117 would be connected to the pipe or conduit 142 and the chamber 153 in the diaphragm valve housing 148. This increased pressure added to that in the port 158 acts on the diaphragm 150 for unseating the valve 159 and connecting the pressure in the pipe or conduit 120 and its branch pipe or conduit 166 with the chamber 153.

The medium in this chamber now under pressure flows into the pipe or conduit 173 and the plunger mechanism 174 for effecting a downward actuation of the plunger 183. The pawl 199 carried by said plunger 183 engages its ratchet 201 for rotating the worm shaft 202 and the worms thereon. It will be appreciated that the direction of movement is now opposite to that above described and as effected by the plunger 182. From this it also follows that, through the same train of mechanism as above described, the plunger 44 will be retracted, permitting the grinding wheel carriage 20 to be oscillated about the trunnion 19 to withdraw the grinding wheel from the work.

When the plunger 183 reaches its lowermost position, it, through a similar mechanism as above described, actuates the valve member 235 of the valve mechanism 172 to its second or right hand position as seen in the drawings for relieving the pressure on top of the plunger 183. The pressure medium in pipes or conduits 120 and 197 flows through the port 196 and acts on the lower piston portion 185 of the plunger 183 for returning it to its normal position. This elevation of the plunger 183 is retarded by the hydraulic resistance or choke coil 254 in the same manner that the similar movement of the plunger 182 was effected for again permitting a time interval between successive operations of the devices. As soon as the plunger 183 is returned to its normal position the valve member 235 is again shifted to the position shown preparatory to a second operation of the device.

From the foregoing it will now be apparent that there has been provided a sizing mechanism adapted to either advance the tool toward the axis of the work or retract same therefrom, depending upon whether the work piece is below the low limit for acceptable work pieces or above the high limit thereof. It will also be noted that the mechanism just described is free of any mechanical linkage in which backlash or spring of the parts can effect the operation thereof, which results in a substantially foolproof mechanism which is highly dependable for producing successive work pieces within the desired limits of tolerance.

It should be noted that the valve member 91 is moved by work pieces that will vary within .001" or a fractional part thereof, thereby merely cracking the ports through which the hydraulic medium flows to either of the conduits 142 and 143. This will naturally result in a relatively small flow; therefore, the pressure developed in the medium is relatively small which, however, is sufficient to actuate the diaphragms 149 and 150 for unseating their respective valves 156 and 159.

There is included in the machine safety means which function in the event the machine is not properly set up to produce work pieces within the desired size. This means includes the valve mechanism shown in Figure 13 and indicated in general by the reference character 255 and shown structurally in Figure 7. As shown in Figure 7, this means or valve comprises a housing which may be the housing 71 having a suitable bore formed therein and spaced ahead of or behind the valve mechanism 118 into which is pressed a valve bushing 256. The valve bushing 256 is provided with a plurality of sets of radial ports 257, 258, 259, 260, 261, and 262, each set being encircled by a similar circumferential groove 263 formed in the exterior of the bushing 256. Disposed within the bore in the bushing 256 is a pair of piston valves 264 and 265. The valve 264 has projecting therefrom a reduced portion 266, while the valve 265 has projecting from opposite ends similar reduced portions 267 and 268. The valve piston 265, in addition, is provided centrally of its ends with a reduced portion or cannelure 269.

The lower end of the valve bushing 256 is closed by a suitable plug or housing 270 containing a piston plunger 271 which abuts on one end with the reduced projection 268 of the piston valve 265. The housing 270 is provided therethrough below the plunger 271 with a port or chamber 273 for introducing hydraulic pressure therein.

for actuating the plunger 271. The upper end of the bushing 256 is closed by a plug 272 against which abuts the reduced portion 266 of the piston valve 264 and acts as a stop to limit the movement of the piston valves 264 and 265 as effected by the plunger 271.

Referring now to Figure 13 it will be noted that the ports 257 and 258 of the bushing 256 have respectively connected therewith one end of pipes 10 or conduits 274 and 275 which respectively have their other ends connected with pipes or conduits 142 and 143. The ports 259 and 262 have respectively connected therewith one end of pipes or conduits 276 and 277 which empty into a pipe 15 or conduit 278, in turn emptying into the main discharge pipe or conduit 126 and therefore the sump or tank 125. The ports 261 have connected therewith one end of a pipe or conduit 279 which has its other end connected with the pipe or conduit 120. The port 273 in the plunger housing 270 has connected therewith one end of a pipe or conduit 280 which terminates at its other end in the branch pressure pipe or conduit 279, and the pipe or conduit 280 includes a hydraulic resistance or choke coil 281. Additionally, the pipe or conduit 280 has connected with it a pipe or conduit 282 which terminates at its other end in the branch discharge pipe or conduit 278 and the said pipe or conduit 282 includes a hydraulic resistance 283. The remaining ports 260 have connected therewith one end of a pipe or a conduit 284 which terminates at its other end in the electrical starting box or panel which controls the operation of the switch for initiating the rotation of the main motor, for example, the motor which effects the rotation of the grinding wheel.

The operation of the safety device just described is as follows:

40 Assuming a work piece considerably undersize or oversize were introduced beneath the gaging plunger 18 which either actuates the valve member 91 above the ports 131 for completely uncovering same or to a position beneath said ports whereby the full flow in the pipe or conduit 117 is delivered therethrough, this would then connect the full pressure in either of the lines 142 or 143. Due to the hydraulic resistances or choke valves 285 and 286 in these lines 45 this full pressure would be directed to either of the piston valves 264 and 265 effecting a descent in either case of the piston valve 265 to uncover the ports 261 of the valve mechanism 255 and close off the ports 259 thereof. This would connect the full pressure in the pipes or conduits 120 and its branch 279 with the pipe or conduit 284 and throw out the starting switch and stopping the machine.

Upon removal of the work from beneath the gaging plunger 18, the pressure is cut off from the pipe or conduit 117 and therefore from the pipes or conduits 142 and 143 whereupon the pressure in the pipe 279 flows through the coil 281 and pipe or conduit 280 to the plunger 271 50 for returning the piston valves 264 and 265 to their normal upper position and relieving the pressure in the pipe or conduit 284 by connecting same with the sump through the pipes or conduits 276, 278, and 126.

70 It should be noted at this time that the pressure acting on the plunger 271 for holding the piston valves 264 and 265 in their upper normal position is stronger than that normally flowing through the pipes or conduits 142 and 143 when the gaging mechanism is in operation, where-

fore the normal operating pressures do not effect the movement of the piston valve 265. However, the pressure acting on the plunger 271 is considerably below the maximum pressure in the pipe or conduit 120 so that when the full pressure is directed against either of the piston valves 264 and 265 their operation is assured. In order, however, to prevent the pressure on said plunger 271 reaching a high enough point to prevent the operation of the device there is 10 an additional bleed through the pipe or conduit 282 and hydraulic resistance or choke coil 283 to the discharge conduits 278 and 126.

The mechanism for throwing out the starting switch by the pressure in pipe or conduit 284 15 is illustrated in Figure 15. As there shown, this mechanism comprises a housing 290 in which is disposed an expandable chamber 291 to which the free end of the pipe or conduit 284 is connected. Extending from the other end of the 20 expandable chamber or member 291 is a stud 292 having connected with its one end a clevis 293. A spring 294 surrounds the stud 292 and has one end abutting the member 291 and the other end abutting one wall of the housing 290 for holding 25 the member 291 in a normal compressed condition.

The clevis 293 has pivotally connected to it one end of an arm 295 which is pivotally mounted at 296 intermediate its ends interiorly of the 30 housing 290. Above the pivot 296 the arm 295 carries a plate 297 from which projects studs 298 and 299 lying on opposite sides of a switch actuating lever 300. The lever 300 is connected at its upper end to the stem of a switch blade 301 35 which bridges switch contacts 302 and 303 carried by the housing 290.

It will be noted that there is considerable lost motion between the studs 298 and 299 of the plate 297 and the lever 300 which is taken up 40 during the expansion of the member 291. In order to effect an instantaneous breaking of the switch contacts this lost motion is utilized as a means for loading a load and fire device operable as soon as the said lost motion has been taken 45 care of. This lost motion comprises a lever 304 pivoted at 305 to a lug interiorly of the housing 290. The lever 304 has formed therein a pair of notches between which a lug 306 is formed having the sides thereof cam shaped and terminating at the base of the notches. Cooperating with said cam lug 306 is the load and fire dog 307 which may be secured to the lever 295 or formed integral therewith and having formed at its free end a cam shaped nose cooperating 50 with the lug 306. In order to maintain operative engagement between the dog 307 and lug 306 the lever 304 has connected therewith one end of a spring 308, acting to complete the movement of the arm 295 and effect a snap breaking 55 action.

The operation of this mechanism is briefly as follows: The pressure from the pipe or conduit 279 is connected through the valve mechanism with the pipe or conduit 284 and the member 291. 60 This pressure causes an expansion of the member 291 against the resistance of the spring 294. The movement of the member 291 carries with it the stud 292 for oscillating the arm 295. This movement of the member 291 substantially takes up 70 the lost motion between the stud 299 and lever 300 and simultaneously disposes the dog 307 on the arm 295 at the top of the cam lug 306. This, of cause, oscillates the load and fire arm 304 about the pivot 305 for loading or tensioning the spring 75

308, whereupon as soon as the dog 307 passes the apex of the lug 306 the spring 308 expands or fires the arm 304 and completes the oscillation of the arm 295 which through the lug 299 oscillates the lever 300 and retracts the switch blade 301 from the switch contacts 302 and 303. It should be noted that this final movement of the arm 295 is independent of any movement of the member 291 or its stud 292 for which purpose the clevis 293 has a pin and slot connection 309 therebetween.

What is claimed is:

1. In a machine tool organization the combination of a bed, a work support on said bed, a tool support on said bed, means for adjusting the position of one of said supports toward and from the other, a sizing member for engagement with a finished work piece, a valve operable by said sizing member, an hydraulically actuated means controlled by the valve and operable on the means for adjusting the position of the movable support for effecting its movement both toward and from the other support.

2. In a machine tool organization the combination of a bed, a work support on said bed, a tool support on said bed, means for adjusting the position of one of said supports toward and from the other, a sizing member for engagement with a finished work piece, a valve operable by said sizing member, hydraulically actuated means controlled by the valve and operable on the means for adjusting the position of the movable support for effecting its movement both toward and from the other support, and means for rendering the sizing device inoperative at the conclusion of either operation of the support adjusting means.

3. In a sizing device of the class described the combination of a contacting member adapted to engage the work to be sized, a pivotally mounted multiplication lever operable by the contacting member, a control valve operable by the lever and movable through a distance greater than that through which the gaging member is moved, a hydraulic circuit controlled by the valve, hydraulic control means in said circuit normally rendered inoperative by the circuit, connections between the valve and control means for rendering same operative, and a feed plunger actuated by said hydraulic control means.

4. In a machine tool organization of the class described the combination with a bed, a work support, and a tool support mounted on said bed, one of said supports being movable relative to the other, of a feed plunger for effecting a movement of said movable support toward the stationary support, a second feed plunger for reversely actuating the shiftable support, a hydraulic circuit for actuating the feed plungers, and a valve in said circuit positionable by the work piece being gaged and connecting the circuit with one or the other of the plungers as determined by the size of the work piece being gaged.

5. In a machine tool organization of the class described the combination with a bed, a work support, and a tool support mounted on said bed, one of said supports being movable relative to the other, of a feed plunger for effecting a movement of said movable support toward the stationary support, a second feed plunger for reversely actuating the shiftable support, a hydraulic circuit for actuating the feed plungers, a valve in said circuit positionable by the work piece being gaged and connecting the circuit

with one or the other of the plungers as determined by the size of the work piece being gaged, and means for retarding the operation of the feed plunger to insure proper positioning of the valve in accordance with the size of the work.

6. In a machine tool organization of the class described the combination with a bed, a work support, and a tool support mounted on said bed, one of said supports being movable relative to the other, of a feed plunger for effecting a movement of said movable support toward the stationary support, a second feed plunger for reversely actuating the shiftable support, a hydraulic circuit for actuating the feed plungers, a valve in said circuit positionable by the work piece being gaged and connecting the circuit with one or the other of the plungers as determined by the size of the work piece being gaged, and means for by-passing the circuit from the feed plunger at the conclusion of the adjusting operation.

7. In a machine tool organization of the class described the combination with a bed, a work support, and a tool support mounted on said bed, one of said supports being movable relative to the other, of a feed plunger for effecting a movement of said movable support toward the stationary support, a second feed plunger for reversely actuating the shiftable support, a hydraulic circuit for actuating the feed plungers, a valve in said circuit positionable by the work piece being gaged and connecting the circuit with one or the other of the plungers as determined by the size of the work piece being gaged, means for by-passing the circuit from the feed plunger at the conclusion of the adjusting operation, means for returning the feed plunger to its initial position, and means for retarding the return of the plunger to effect a time interval between successive feeding operations to permit a replacement of the work piece being gaged.

8. In a machine tool organization of the class described the combination with a bed, a work support and a tool support mounted thereon, one for adjustment toward and from the other, of means for effecting said adjustment at incremental rates toward and from the other support, means for gauging a work piece held by the work support and automatically operable means for actuating said feed adjusting means in reverse directions in accordance with the variance from prescribed size of a work piece being gaged.

9. In a machine tool organization of the class described the combination with a bed, a work support mounted on said bed, a tool support mounted on said bed, one of said supports mounted on the bed for adjustment toward and from the other, and means for effecting said adjustment, of a sizing device including a work piece contacting member, and automatic means controlled by said contacting member for actuating the support adjusting means in reverse directions in accordance with the size device determined dimension of the work piece for correspondingly reversely adjusting the position of the said support.

10. In a machine tool organization of the class described the combination with a bed, a work support mounted on said bed, a tool support mounted on said bed, one of said supports mounted on the bed for adjustment toward and from the other, and means for effecting said adjustment, of a sizing device including a contacting member, a pair of feed plungers respectively operable on the support adjusting means

- to shift the movable support toward and from the other support, and automatically operable means between the contacting member and the feed plungers for independently actuating said 5 plungers in accordance with the size of the work piece being gaged.
11. In a machine tool organization of the class described the combination with a bed, a work support mounted on said bed, a tool support 10 mounted on said bed, one of said supports mounted on the bed for adjustment toward and from the other, and means for effecting said adjustment, of a sizing device including a contacting member, a pair of feed plungers respectively 15 operable on the support adjusting means to shift the movable support toward and from the other support, automatically operable means between the contacting member and the feed plungers for independently actuating said 20 plungers in accordance with the size of the work piece being gaged, and means operable at the conclusion of the feeding stroke for returning the feed plunger to its inoperative position.
12. In a machine tool organization of the class 25 described the combination with a bed, a work support mounted on said bed, a tool support mounted on said bed, one of said supports being mounted on the bed for adjustment toward and from the other, and means for effecting said adjustment, of a sizing device including a contacting member, a pair of feed plungers respectively 30 operable on the support adjusting means to shift the movable support toward and from the other support, automatically operable means between the contacting member and the feed plungers for independently actuating said 35 plungers in accordance with the size of the work piece being gaged, means operable at the conclusion of the feeding stroke for returning the feed plunger to its inoperative position, and means retarding the 40 operation of the return of the feed plunger to permit a replacement of the work piece being gaged.
13. In a sizing device for use with machine tools 45 the combination with a tool support and a work support one of which is movable toward and from the other, of means for effecting the movement of said movable support at incremental rates in reverse directions comprising a pair of hydraulically actuable feed plungers, a pawl on each of said plungers, a ratchet for each pawl and effective respectively for rotation in opposite directions, a hydraulic circuit for the plungers, a valve mechanism in the circuit for normally rendering the pawls inoperative, and a second valve in said circuit and positionable by a work piece for operating the last mentioned valve mechanism for thereby connecting the circuit with one or the other of the feed plungers.
14. In a sizing device for use with machine tools 50 the combination with a tool support and a work support one of which is movable toward and from the other, of means for effecting the movement of said movable support at incremental rates in reverse directions comprising a pair of hydraulically actuable feed plungers, a pawl on each of said plungers, a ratchet for each pawl and effective respectively for rotation in opposite directions, a hydraulic circuit for the plungers, a 55 valve mechanism in the circuit for normally rendering the pawls inoperative, a second valve in said circuit and positionable by a work piece for operating the last mentioned valve mechanism for thereby connecting the circuit with one or the other of the feed plungers, and additional 60
- 75

valve means in the circuit for delaying the operation of the first valve mechanism by the second valve to insure the proper positioning of the work being gaged.

15. In a sizing device for use with machine tools 5 the combination with a tool support and a work support one of which is movable toward and from the other, of means for effecting the movement of said movable support at incremental rates in reverse directions comprising a pair of hydraulically actuable feed plungers, a pawl on each of said plungers, a ratchet for each pawl and effective respectively for rotation in opposite directions, a hydraulic circuit for the plungers, a valve mechanism in the circuit for normally rendering the pawls inoperative, a second valve in said circuit and positionable by a work piece for operating the last mentioned valve mechanism for thereby connecting the circuit with one or the other of the feed plungers, means in the circuit for delaying the operation of the first valve mechanism by the second valve to insure the proper positioning of the work being gaged, and means for adjustably varying the delay.

16. In a gaging mechanism for use with machine tool structures the combination with a work support and a tool support one of which is movable toward and from the other, of reversely actuable means for effecting said adjustment of the support, a first feed plunger for actuating the support adjusting means in one direction, a second feed plunger for actuating the support adjusting means in the opposite direction, a hydraulic circuit adapted to be connected selectively with said plungers, a valve mechanism normally rendered inoperative by the hydraulic circuit for disconnecting the circuit from the feed plungers, and a second valve in the circuit positionable by a work piece being gaged for actuating the valve mechanism and connecting the hydraulic circuit through the valve mechanism with one of said feed plungers in accordance with the size of the work for thereby either advancing or retracting the movable support relative to the fixed support.

17. In a gaging mechanism for use with machine tool structures the combination with a work support and a tool support one of which is movable toward and from the other, of reversely actuable means for effecting said adjustment of the support, a first feed plunger for actuating the support adjusting means in one direction, a second feed plunger for actuating the support adjusting means in the opposite direction, a hydraulic circuit adapted to be connected selectively with said plungers, a valve mechanism normally rendered inoperative by the hydraulic circuit for disconnecting the circuit from the feed plungers, a second valve in the circuit positionable by a work piece being gaged for actuating the valve mechanism and connecting the hydraulic circuit through the valve mechanism with one of said feed plungers in accordance with the size of the work for thereby either advancing or retracting the movable support relative to the fixed support, and means operable by the feed plungers for returning same to their initial position after the completion of a feed adjusting stroke.

18. In a gaging mechanism for use with machine tool structures the combination with a work support and a tool support one of which is movable toward and from the other, of reversely actuable means for effecting said adjustment of the support, a first feed plunger for actuating

the support adjusting means in one direction, a second feed plunger for actuating the support adjusting means in the opposite direction, a hydraulic circuit adapted to be connected selectively with said plungers, a valve mechanism normally rendered inoperative by the hydraulic circuit for disconnecting the circuit from the feed plungers, a second valve in the circuit positionable by a work piece being gaged for actuating the valve mechanism and connecting the hydraulic circuit through the valve mechanism with one of said feed plungers in accordance with the size of the work for thereby either advancing or retracting the movable support relative to the fixed support, means operable by the feed plungers for returning same to their initial position after the completion of a feed adjusting stroke, and means retarding the return of the feed plunger to provide a time interval for the replacement of the work being gaged.

19. In a grinding machine of the class described, the combination with a work support and a wheel support one of which supports is movable toward and from the other, of means for effecting the movement of said movable support, a sizing mechanism associated with the work support and movable by a finished work piece, control means operable by said sizing mechanism for actuating the moving means, and additional means operated by said control means for stopping the entire machine if the work piece is beyond definite size.

20. A work size controlling device for use in connection with a machine tool including a work support, a tool support and means for effecting movement of the supports toward and from each other, said gauging device including hydraulically actuatable means for determining the relative movements of the work and tool supports and control mechanism therefor including a deflectible sizing member, means for rendering the controlling device inoperative when the sizing member is undeflected, means responsive to initial deflection of said member for effecting relative movement of the supports in one direction, and means responsive to additional deflection thereof for effecting relative movement of the supports in an opposite direction.

21. A sizing device for utilization with a machine tool or the like including tool and work supports and means for effecting relative approach and retraction of said supports, said device including a member having a potential intermediate neutral position and mounted for opposite deflections with respect thereto, means for rendering the device positively inoperative upon maximum deflection of said member in one direction, and means for stopping the operation of the associated tool on over deflection of said member in the opposite direction.

22. A sizing device for utilization with a machine tool or the like including tool and work

supports and means for effecting relative approach and retraction of said supports, said device including a member having a potential intermediate neutral position and mounted for opposite deflections with respect thereto, means for rendering the device positively inoperative upon maximum deflection of said member in one direction, and means for stopping the operation of the associated tool on over deflection of said member in the opposite direction, said deflectible member having additional potential effective positions intermediate the neutral and said extremes and means activated by shifting of said member to said intermediate positions for effecting a relative movement of the tool and work supports. 15

23. A sizing device for utilization with a machine tool or the like including tool and work supports and means for effecting relative approach and retraction of said supports, said device including a member having a potential intermediate neutral position and mounted for opposite deflections with respect thereto, means for rendering the device positively inoperative upon maximum deflection of said member in one direction, and means for stopping the operation of the associated tool on over deflection of said member in the opposite direction, said deflectible member having additional potential effective positions intermediate the neutral and said extremes, a first means activated by positioning of said member in one of said intermediate locations for effecting relative approach of the tool and work support, and a second means activated by positioning of said member at the opposite of said intermediate positions for effecting relative separation of said tool and work supporting members.

24. A gauging device for utilization in conjunction with a machine tool or the like which includes a work support, a tool support, and means for effecting relative incremental movements of said supports either toward or away from each other, said gauging mechanism including separate motive devices for effecting approaching and retracting movements of the work and tool supports and a multi-position deflectible member engageable by a work piece for determining said movements, said deflectible member having a first position effective when unengaged by a work piece to prevent operation of the motive devices, a second semi-deflected position when engaged by a work piece effective to determine incremental separating movements of the tool and work supports, a second deflected position effective to neutralize the action of said motive means, and an additional deflected position effective on an engagement of an oversize work piece therewith for activating the other of said motive means to effect a relative incremental approach of said work and tool supports substantially as and for the purpose described. 40 45 50 55 60
